UNITED STATES PATENT OFFICE.

ORIEN S. LOVELY, OF COLCHESTER, ILLINOIS.

COMBINED CURRYCOMB AND CLEANER.

1,014,160.

Specification of Letters Patent.

Patented Jan. 9, 1912.

Application filed June 3, 1911. Serial No. 631,151.

To all whom it may concern:

Be it known that I, ORIEN S. LOVELY, a citizen of the United States, residing at Colchester, in the county of McDonough and 5 State of Illinois, have invented a new and useful Combined Currycomb and Cleaner; and I do hereby declare the following to be a full, clear, and exact description of the invention, such as will enable others skilled 10 in the art to which it appertains to make and use the same.

This invention relates to a new and useful curry comb.

The principal object of the present invention is to provide a novel form of cleaner for 15 efficiently and thoroughly removing the dirt, hair, &c., from the teeth of the comb.

A further object of the invention is to improve generally the construction of curry, 20 combs.

The invention comprises further features and combination of parts, as hereinafter set forth in the drawings, and claimed.

In the drawings:—Figure 1 is a view in 25 perspective of a curry comb constructed in accordance with the invention. Fig. 2 is a bottom plan view. Fig. 3 is a sectional view on line 3—3 of Fig. 1. Fig. 4 is a sectional view on line 4—4 of Fig. 1, taken through 30 the hinge between the curry comb and the cleaner. Fig. 5 is a detail view of the cleaner, detached.

Referring more especially to the drawings 1 designates the curry comb, which is rectangular in contour, and provided with a 35 usual handle 2, which is provided with a forked member 3 riveted to the curry comb, as shown at 4. The curry comb 1 is provided with the usual teeth 5 between which 40 the cleaner 6 is arranged.

The cleaner 6 is rectangular in shape and comprises the end pieces 7 and 8, to which the cleaning bars 9 are riveted as shown at 10. Two of the bars 9 are provided with 45 extending leaf lugs 11, which terminate into rolls 12, forming parts of the hinge 13 between the cleaner and the curry comb. The other parts 14 of the hinge are connected so as to coöperate with the rolls 12 by means

of the rod or bolt 15. Surrounding the rod 50 or bolt 15 is a coil spring 16, one end of which is received by an opening 17^a of one of the bars 9, and finally extended into a depression 17 of the piece 7 thus anchoring one end of the spring. This end portion is 55 also arranged between two lugs 18 and 19 of the end bar 7 of the cleaner, while the other end of the spring is arranged in any one of the apertures 19^a of one of the parts 14 of the hinge. The object in providing more 60 than one of the apertures 19^a, is to permit the spring to be tightened, when it becomes weak. Arranged on the rod or bolt 15, in order to hold the spring in place is a fiber sleeve 20. 65

The cleaner it will be observed is so connected to the curry comb that upon a reverse stroke, while currying a horse, the cleaner will be forced outwardly of the teeth of the comb, by imparting a twisting jerk 70 to the comb, and when the user starts the succeeding forward stroke, the cleaner has returned to its normal position, by the action of the spring.

From the foregoing it will be apparent 75 that there has been devised a simple, novel and practical cleaner for curry combs, and one which has been found to be exceedingly useful, for it obviates the necessity of picking the hair and dirt from the comb. 80

The invention having been set forth, what is claimed as new and useful is:—

In combination, a curry comb having teeth and provided with hinged members, a cleaner having hinge members, a bolt passing through the hinge members for connecting the cleaner hingedly to the curry comb, the cleaner having a pair of lugs and comprising a pair of end bars and a plurality of transversely extending flat bars, one of the end bars having a depression, while one of the flat bars is provided with an opening registering with the depression, a spring coiled about the bolt having one end adjustably anchored to one of the hinge members 90 of the curry comb, while the other end is extended downwardly and arranged between the lugs, the downwardly extending end of 95

the spring terminating into an angle portion arranged in the opening, the angle portion having an upturned lug received by the depression, the opening, the depression and the 5 lugs constituting means to prevent displacement of the downwardly extending end of the spring.

In testimony whereof I have signed my name to this specification in the presence of two subscribing witnesses.

ORIEN S. LOVELY.
